ABSTRACT

A pulse generating circuit includes time constant circuits, switching circuits, and means to apply the output signals of the time constant circuits to the switching circuits, whereby a pulse signal suitable as, for example, a clear signal is generated at a predetermined time after the closure of a power switch.

PULSE GENERATING CIRCUIT

BACKGROUND OF THE INVENTION

The present invention relates to a pulse generating circuit and, more particularly, to a pulse generating circuit which is applied to, for example, an automatic clear circuit of an electronic portable calculator.

DESCRIPTION OF THE PRIOR ART

FIG. 1 shows an example of a prior-art pulse generating circuit, which is especially applicable to an automatic clear circuit of an electronic portable calculator. Referring to the figure, C_1 designates a capacitor, R_1 and R_2 resistors, T_1 an MOS type field effect transistor, Sw_1 a power switch, Sw_2 a clearing switch, O_1 an output terminal for transmitting a clear signal, and $-V_{CC_1}$ a power source.

With such a construction, at the same time that the power switch Sw_1 is turned on the field effect transistor T_1 is brought into the "on" state, to clear the electronic portable calculator. When, thereafter, the voltage across the resistor R_1 becomes lower than the threshold voltage of the field effect transistor T_1 , after a certain period of time, according to the time constant of the capacitor C_1 and the resistor R_1 , the field effect transistor T_1 is brought into the "off" state. Thus, the automatic clearing function is effected.

SUMMARY OF THE INVENTION

An object of the present invention is to provide a pulse generating circuit by which a pulse signal, for example, one suitable as a clear signal, is generated at a predetermined time after a power switch has been turned-on.

Another object of the present invention is to provide a pulse generating circuit of simple construction.

Still another object of the present invention is to provide an inexpensive pulse generating circuit.

BRIEF DESCRIPTION OF THE DRAWINGS

FIG. 1 is a circuit diagram showing an example of a prior-art pulse generating circuit;

FIG. 2 is a circuit diagram showing an embodiment of a pulse generating circuit according to the present invention;

FIGS. 3a-3c are diagrams for explaining the operation of the embodiment in FIG. 2;

FIGS. 4 to 6 are circuit diagrams showing different embodiments of the pulse generating circuit according to the present invention; and

FIG. 7 is a block diagram showing a concrete example in which the pulse generating circuit of the present invention is applied to a gate circuit of an electronic portable calculator.

PREFERRED EMBODIMENTS OF THE INVENTION

Description will be made hereunder in conjunction with a few embodiments of the invention, reference being had to FIGS. 2 to 7. In the figures, the same parts or parts having the same functions are assigned with the same symbols.

FIG. 2 shows an embodiment of a pulse generating circuit according to the present invention. In the figure, T_2 and T_3 designate bipolar type transistors. The collector electrode of the transistor T_2 is connected through a resistor R_6 and a power switch Sw_2 to a power source

$-V_{CC_2}$. The base electrode of the transistor T_2 is connected through a capacitor C_2 to ground, and through a resistor R_3 to the power switch Sw_2 . The emitter electrode of the transistor T_3 is grounded, while the collector electrode of the transistor T_3 is connected to the emitter electrode of the transistor T_2 . The base electrode of the transistor T_3 is grounded through resistors R_5 and R_4 . The base electrode of the transistor T_3 is also connected through the resistor R_5 and a capacitor C_3 to the power switch Sw_2 . O_2 indicates an output terminal which is connected to the collector electrode of the transistor T_2 . Sw_3 is a switch, such as a clearing switch, which is arranged between the collector electrode of the transistor T_2 and ground. In this case, the respective values of the resistors R_3 and R_4 and the capacitors C_2 and C_3 are so set as to obtain the operation illustrated in FIGS. 3a-3c.

At a time t_0 , the power switch Sw_2 is thrown to the position of a contact a . A series connection consisting of the resistor R_3 and the capacitor C_2 constitutes an integrating circuit. The transistor T_2 , immediately after the closure of the power switch, is in the "off" state since the terminal voltage of the capacitor C_2 does not instantly become greater than the base-emitter-ground threshold voltage of the transistor T_2 . Similarly, the transistor T_3 is in the "on" state. A base current, which is limited to a safe value by the resistor R_5 flows through the capacitor C_3 .

After the time t_0 at which the power switch Sw_2 has been thrown to the position of the contact a , the capacitor C_2 is gradually charged. When, as a result, the terminal voltage of the capacitor C_2 exceeds the threshold voltage of the transistor T_2 at a time t_1 as illustrated in FIG. 3a, the transistor T_2 is turned "on". The capacitor C_3 is charged through the resistor R_4 and the resistor R_5 as well as the transistor T_3 , and its charging current decreases. The transistor T_3 is turned "off" at a time t_2 at which, as illustrated in FIG. 3b, the base-emitter-ground voltage of the transistor T_3 becomes smaller than the threshold voltage due to the charging of the capacitor C_3 . Accordingly, as illustrated in FIG. 3c, both the transistors T_2 and T_3 are in the "on" state during the period of time from t_1 to t_2 . Thus, an output suitable as, for example, a clear signal is obtained from the output terminal O_2 . In this case, the times t_1 and t_2 can be controlled to arbitrary ones by appropriately setting the respective values of the resistor R_3 , as well as the capacitor C_2 , and the resistor R_4 , as well as the capacitor C_3 .

After the t_2 at which the signal output is provided from the output terminal O_2 , the signal output can be arbitrarily transmitted by the use of the switch Sw_3 .

In order to turn the power switch Sw_2 off, it may be changed-over to the position of a contact b , to thereby discharge the capacitors C_2 and C_3 . A resistor R_7 may be connected between the power source and the ground, so as to discharge them through the resistance.

FIG. 4 shows another embodiment of the pulse generating circuit according to the present invention. A point of difference from the embodiment in FIG. 2 resides in the use of MOS type field effect transistors as T_2 and T_3 . The input impedance of the field effect transistor is extremely high, so that the protective resistor R_5 as in the previous embodiment is not required.

FIG. 5 shows a further embodiment of the pulse generating circuit according to the present invention. The

differences from the embodiment in FIG. 4 are that one output electrode of each of the MOS type field effect transistors T_2 and T_3 is grounded, and that the other output electrodes of the respective MOS type field effect transistors T_2 and T_3 are connected in common, the connection point being connected through the resistor R_6 and the power switch Sw_2 to a power source V_{cc} . The output terminal O_2 is connected to the common connection point. The time constant of $C_2 \times R_3$ is made larger than that of $C_3 \times R_4$. A pulse obtained at the output terminal O_2 is equivalent to one resulting from the inversion of the pulse in any previous embodiment.

FIG. 6 shows a yet further embodiment of the pulse generating circuit according to the present invention. The difference from the embodiment in FIG. 5 resides in the use of bipolar transistors as T_2 and T_3 .

The circuit operations of the embodiments in FIG. 4 to FIG. 6 are similar to that of FIG. 2. In the circuits in FIGS. 2 and 4, the "off" state of the two transistors have preference. In contrast, in the circuits in FIGS. 5 and 6, the "on" state of the two transistors have preference.

FIG. 7 shows a concrete example of a circuit in which the pulse generating circuit of the present invention is applied to a gate circuit of an electronic portable calculator. In the figure, CL designates a clear signal input terminal to which the terminal O_2 of the circuit of any embodiment discussed above is connected. $K_1, K_2, \dots, K_4$ indicate key input terminals. The input terminals CL and $K_1, K_2, \dots, K_4$ constitute an input signal source IS . R_1 represents an OR circuit, F_1 and F_2 flip-flop circuits, IN an inverter, and A_1 and A_2 AND circuit. These components R_1, F_1, F_2, IN and A_1 constitute a start pulse generator PG . A_{11} to A_{15} represents AND circuits, which constitute a gate circuit G . Shown at $O_{11}, \dots, O_{15}$ are output terminals to which outputs of the AND circuits $A_{11}, \dots, A_{15}$ are respectively supplied.

The flip-flop circuits F_1 and F_2 of the start pulse generating circuit PG are triggered by a word pulse of the calculator. With the trigger at this time, a signal having been in the flip-flop circuit F_1 is delivered to the flip-flop circuit F_2 , and signals having been delivered to the input terminals CL and K_1 to K_4 are delivered to the flip-flop circuit F_1 .

When the outputs of the flip-flop circuits F_1 and F_2 become "1" and "0", respectively, the start pulse generating circuit PG opens the gates A_{11} to A_{15} of the gate circuit G .

That is, the signal supplied to the input terminals CL and K_1 to K_4 are transferred to the output terminals O_{11} to O_{15} after they are adjusted in time and in period by the word pulses.

The auto-clear signal illustrated in FIG. 3 has the logical value of "0" from the closure of the power source till the time t_1 , the period between them being enough to make the flip-flop circuits F_1 and F_2 operable and to make the values of the circuits F_1 and F_2 the logical values of "0" and "0" by means of the auto-clear signal. It has the logical value of "1" during the period from the time t_1 till the time t_2 at which at least 1 word pulse period of the calculator has elapsed. It has the logical value of "0" after the time t_2 .

Accordingly, the flip-flop circuits F_1 and F_2 have the logical values changed from "0", "0" to "1", "0" during the period from the time t_1 to the lapse of 1 word

pulse period. As a result, the gate A_{11} is opened, to transfer the clear signal from the input terminal CL to the output terminal O_{11} . If the clear signal has the logical value of "1" consecutively, the flip-flop circuits F_1 and F_2 fall into the logical values of "1" and "1" in the next word period. The gate A_{11} is, accordingly, closed. Similarly, when the auto-clear signal falls into the logical value of "0" after the time t_2 , the circuits F_1 and F_2 fall into the logical values of "0" and "1" or "0" and "0". Therefore, the gate A_{11} remains closed, and the clearing procedure of the calculator with the clear key Sw_3 is then made possible.

Although, in the foregoing embodiments, two sets of series circuits are employed which are connected in parallel between the power switch Sw_2 and ground so as to be opposite in the positions of the constituent elements to each other and each of which consists of the capacitor and the resistor, it is a matter of course that the present invention is not restricted thereto.

Although, in the embodiments, the transistors T_2 and T_3 are employed as the switching elements, it is a matter of course that the present invention is not restricted thereto. For example, silicon controlled rectifiers may be used.

In the embodiments, the power source — V_{cc2} or V_{cc} is used. However, it is a matter of course that the invention is not restricted thereto, but that the polarities of the power source may be reversed. In this case, it is required to change, e.g., the polarity of the transistors as may be needed. Concerning the signal output, the two cases are considered as stated previously.

Needless to say, the present invention is not restricted to the foregoing embodiments, but a variety of applications and modifications can be considered.

As described above, with the pulse generating circuit according to the present invention, such various advantages are brought forth that a pulse signal can be generated by a simple construction at a predetermined time after turning a power switch, and that the circuit arrangement is inexpensive.

What we claim:

1. A pulse generating circuit comprising:
first and second switching means each having first and second electrodes and a control electrode and having one of a conductive and a non-conductive state in response to an input connected to control electrode;
time constant circuit means connected to said control electrodes of said switching means responsive to the connection of a reference potential thereto, for making said first switching means sustain one of the conductive and non-conductive states until a first instant of time and fall into the other state after the first instant of time, and for making said second switching means sustain said other state until a second instant of time and fall into said one state after said second instant of time, said first instant of time occurring prior to said second instant of time;
an output terminal connected to the first electrode of one of said switching means; and
substantially zero impedance means for connecting the first electrode of the other of said switching means with one of the first and second electrodes of said one switching means so as to supply said output terminal with a pulse signal determined by said other state of both of said switching means

during the period of time between said first and second instants of time.

2. A pulse generating circuit according to claim 1, wherein said switching means are connected in series.

3. A pulse generating circuit according to claim 1, wherein said switching means are connected in parallel.

4. A pulse generating circuit comprising:
 first means, responsive to the connection of a first reference potential thereto at a first instant of time, for generating a first constant output voltage level for a preselected period of time until a second instant of time;
 second means, responsive to the connection of said first reference potential thereto at said first instant of time, for generating said first output voltage after a specified period of time has elapsed from said first instant of time prior to said second instant of time; and
 third means, responsive to the output voltage levels generated by said first and second means, for providing a signal at said first voltage level for the period of time during which both the outputs of said first and second means are at said first output voltage level.

5. A pulse generating circuit according to claim 4, wherein each of said first and second means comprises an electronic switching element, having an input electrode, a control electrode, and an output electrode and having a time constant network connected to the control electrode thereof and being switchably coupled to a source of said first reference potential, and wherein said third means is connected to the output electrode of one of said electronic switching elements, while one of the input and output electrodes of the other electronic switching element is connected to one of the input and output electrodes of said one electronic switching element.

6. A pulse generating circuit according to claim 5, 40

wherein each of said time constant networks comprises a series connection of a resistor and a capacitor switchably connected between said source of first reference potential and a source of a second reference potential, the control electrodes of said electronic switching elements being connected respectively to the common connection of the resistor and capacitor of each network.

7. A pulse generating circuit according to claim 6, wherein one of said networks has the resistor thereof switchably connected to said source of first reference potential while the other of said networks has the capacitor thereof switchably connected to said source of first reference potential.

8. A pulse generating circuit according to claim 5, wherein said electronic switching elements have their input and output electrode connected in series.

9. A pulse generating circuit according to claim 5, wherein said electronic switching elements have their input and output electrodes connected in parallel.

10. A pulse generating circuit according to claim 7, wherein each of said electronic switching elements comprise a bipolar transistor, with the collector of at least one of said transistors connected to said third means.

11. A pulse generating circuit according to claim 7, wherein each of said electronic switching elements comprises a field effect transistor wherein the drain electrode of at least one of said transistors is connected to said third means.

12. A pulse generating circuit according to claim 5, further including a bias resistor switchably connected between said source of first reference potential and the output electrode of one of said electronic switching elements.

13. A pulse generating circuit according to claim 5, further including a power switch connected between a source of said first reference potential and each of said first and second means.
